(57) **CLAIM**

The ornamental design for an upper, as shown and described.

DESCRIPTION

FIG. 1 is a rear, right, top perspective view of the first embodiment of the upper, showing our new design;
FIG. 2 is a front, left, bottom perspective view thereof;
FIG. 3 is a right side elevational view thereof;
FIG. 4 is a left side elevational view thereof;
FIG. 5 is a front elevational view thereof;
FIG. 6 is a rear elevational view thereof;
FIG. 7 is a top plan view thereof;
FIG. 8 is a bottom plan view thereof;
FIG. 9 is an enlarged view of detail 9 in FIG. 5;
FIG. 10 is an enlarged view of detail 10 in FIG. 6;
FIG. 11 is an enlarged view of detail 11 in FIG. 6;
FIG. 12 is an enlarged view of detail 12 in FIG. 6;
FIG. 13 is an enlarged view of detail 13 in FIG. 6;
FIG. 14 is an enlarged view of detail 14 in FIG. 7;
FIG. 15 is an enlarged view of detail 15 in FIG. 7;
FIG. 16 is an enlarged view of detail 16 in FIG. 8;
FIG. 17 is an enlarged view of detail 17 in FIG. 8;
FIG. 18 is a rear, right, top perspective view of the second embodiment of the upper, showing our new design;
FIG. 19 is a front, left, bottom perspective view thereof;
FIG. 20 is a right side elevational view thereof;
FIG. 21 is a left side elevational view thereof;
FIG. 22 is a front elevational view thereof;
FIG. 23 is a rear elevational view thereof;
FIG. 24 is a top plan view thereof;
FIG. 25 is a bottom plan view thereof;
FIG. 26 is an enlarged view of detail 26 in FIG. 22;
FIG. 27 is an enlarged view of detail 27 in FIG. 22;
FIG. 28 is an enlarged view of detail 28 in FIG. 23;
FIG. 29 is an enlarged view of detail 29 in FIG. 23;
FIG. 30 is an enlarged view of detail 30 in FIG. 24;
FIG. 31 is an enlarged view of detail 31 in FIG. 24;
FIG. 32 is an enlarged view of detail 32 in FIG. 24; and,
FIG. 33 is an enlarged view of detail 33 in FIG. 25.
The dashed broken lines in the figures illustrate portions of the upper that form no part of the claimed design.
The dash-dot-dash broken lines are for notating enlarged views and form no part of the claimed design.
